DESIGN FOR A REFLECTING SIGN

Harold L. Van Doren and Donald E. Dailey,
Toledo, Ohio, assignors to Western Cataphote
Corporation, Toledo, Ohio, a corporation of
Ohio

Application November 21, 1939, Serial No. 88,389

Term of patent 7 years

To all whom it may concern:

Be it known that we, Harold L. Van Doren and Donald E. Dailey, citizens of the United States, and residents of Toledo, in the county of Lucas and State of Ohio, have invented a new, original, and ornamental Design for a Reflecting Sign, of which the following is a specification, reference being had to the accompanying drawing, forming a part thereof.

Fig. 1 is a front elevation of a reflecting sign, showing our new design, and Fig. 2 is an end view thereof.

The dominant features of the design reside in the portions shown in full lines.

The portion bearing the numbers is glass and has a pebbled outer surface with dark background and the characters are provided at the rear of the glass and having a light reflecting characteristic. The particular numbers shown are merely illustrative.

We claim:

The ornamental design for a reflecting sign, substantially as shown and described.

HAROLD L. VAN DOREN.
DONALD E. DAILEY.
